OIL GAS GENERATOR

Original Filed Nov. 9, 1929

UNITED STATES PATENT OFFICE

LEONARD B. HARRIS, OF NEW YORK, N. Y., ASSIGNOR, BY MESNE ASSIGNMENTS, TO INTERNATIONAL OIL GAS CORPORATION, OF DOVER, DELAWARE, A CORPORATION OF DELAWARE

OIL GAS GENERATOR

Application filed November 9, 1929, Serial No. 405,913. Renewed April 16, 1932.

This invention relates to an oil gas generator and process of producing gas from hydrocarbon oils by causing the same to react with steam. The oil and steam are heated 5 to a high temperature by means of a heating medium, such as hot products of combustion, for example, that does not come into actual contact with the oil and steam.

In carrying out the invention, the oil is atomized and fed into the gas generating retorts where the oil meets jets of steam and reaction takes place, there being one individually hydraulically and intermittently operated atomizer for each retort. The invention also 10 includes means by which the supply of the gas making mediums to the oil gas generating retorts can be accurately controlled, with respect to the time of admission of the gas making mediums, the quantity delivered and 15 the sequence in which the retorts operate.

The invention will be understood from the description in connection with the accompanying drawing in which Fig. 1 is a vertical section through the oil gas generator with a gas scrubber shown partly in side elevation and partly in section attached to the oil gas generator; and Fig. 2 is a vertical 20 section through one of the retorts in entirety together with its individual hydraulically and intermittently operated atomizer.

In the drawing, reference character 1 indicates a metal container, preferably circular in cross section, that is lined on the inside with refractory material 2, such as brick. The lower portion 3 of the container represents the combustion chamber proper into 25 which fuel can be introduced through the side walls of the device by means of burners (not shown), or in any other convenient or desirable way. The top of the container 1 is covered by means of the metal plate 4 that is provided with an outlet at the center to which the stack 5 for waste products of combustion is connected. A damper 6 is provided in this stack.

An annular header 7 made of a high heat resisting alloy containing a metal such as nickel, for example, which will act as a catalyst, is connected to the lower side of the 30 cover 4 and surrounds the opening through

which the waste products pass to the stack 5. The header 7 is connected to the cover 4 by means of the bolts 8. A circular row of retorts 9, also made of high heat resisting alloy, which may contain a metal such as 55 nickel, for example, to act as a catalyst, having their lower ends closed, depends from the lower side of the header 7 with their upper open ends extending into this header. A disc-shaped baffle 10 of refractory material 60 is suspended by means of rods 11 from the cover 4 within the row of retorts 9 below the opening for the stack 5.

A row of tubes 12, containing a very high 65 percentage of nickel or other catalyst, corresponding in numbers and centers to the retorts 9, having smaller external diameters than the internal diameters of the retorts 9, extends through the cover plate 4 almost to the bottom of the retorts 9 and have their 70 lower ends open. The upper ends of the tubes 12 are threaded and are screwed into threaded openings in the plate 4. Lock nuts 13 clamp the tubes in place in the plate 4. Atomizers 14, to be described later, are located at the upper open ends of each of the respective tubes 12. A pipe 15 from a source of water (not shown) and having a hand controlled valve 16, a regulating contactor 16' and a sight feed 16'' leads to a heating coil 17 that 75 is located in the lower end of the stack 5. A pipe 18 leads from the coil 17 to the annular header 19 located above the plate 4. Branch pipes 20 lead from the header 19 to 80 the atomizers 14.

An oil reservoir 21 contains a plurality of single acting intermittently actuated and individually timed oil measuring pumps 48 of a well known sort, and pipes 22 lead from 85 these pumps to the respective atomizers 14.

It is to be noted that the word "timed" 90 as applied to the pumps, employed in combination with the other apparatus comprising this invention, relates to the sequence or rotation in which the impulses or delivery strokes of the individual pumps are related with respect to each other, such as overlapping or staggered, and that the respective retorts and atomizers being cooperatively as- 95 100

sociated with the pumps, the retorts also operate in overlapping or staggered rotation.

It is also to be noted that while only one oil pump 48 is visible in the end view of the 5 tank or reservoir 21, shown in Figure 1, it is to be understood that there is a plurality of other similar pumps 48 behind and in line with the one shown, as just mentioned.

An oil gas outlet pipe 23 leads from the 10 header 7 to a gas scrubber 24 of a well known type. The outer periphery of the scrubber 24, being partly broken away to show a "water level" therein as indicated by W. L. A 15 valved branch pipe 25 is connected to the pipe 23 and a branch pipe 26 leads into a sump 27 that contains liquid of sufficient depth to seal the lower end of the branch pipe 26. A pipe 28 for washed gas leads to a gas box 29 from which a pipe 30 with 20 a test cock 30' leads to a gas main or place of consumption of the gas which is not shown.

Each one of the atomizers 14 (Fig. 2) at the upper ends of the tubes 12 comprises a 25 body portion 31, having a flange 32 that rests upon the upper end of the tube 12. A threaded thimble 33 keeps the body portion 31 in firm contact with the tube 12. An opening 34 is provided in the side of the 30 atomizer for the pipe 20 and a port 35 leads from the opening 34 to an annular space 36 at the lower end of the body portion 31. A ring 37 having a series of holes 38 therethrough is screwed upon the lower threaded 35 end of the body portion 31 of the atomizer, so that the holes 38 communicate with the annular space 36. These holes 38 may be parallel, inclined or spiral.

A central hole 39 extends through the body 40 portion 31 and a conically-shaped valve seat 40 is provided at the bottom. An atomizer spindle 41 with a conically-shaped lower end to form a valve is located in the hole 39. A head piece 42 is threaded upon the upper 45 end of the body portion 31 and is provided with a central opening through which the spindle 41 extends. A hole 43 is provided in one side of the head piece 42 for the oil pipe 22. A flexible diaphragm 44 is placed at the 50 upper end of the spindle 41 and is clamped to the spindle by threaded nuts on opposite sides of the diaphragm. The peripheral circumferential edge of the diaphragm 44 is 55 clamped in place against a shoulder in the head piece 42 by means of a hollow threaded nut 45 screwed into the internally threaded recess 46 in the head piece 42. A compression spring 47 is interposed between the top 60 of the hollow nut 45 and the upper nut on the spindle 41 tending to keep the valve 40 closed. The hole 43 enters the head piece 42 at a point below the diaphragm 44, so that 65 oil under pressure entering through the pipe 22 will cause the diaphragm to yield and

the spindle to lift in synchronism with the oil measuring pumps.

The operation is as follows:

The oil gas generating retorts are heated by combustion of fuel in the lower portion 3 thereof and the hot products contact with the outside of the retorts 9 and pass around the edge of the baffle 10 into the stack 5. Water in an amount that is regulated by the 70 regulating contactor 16' passes into the heater 17 where steam is generated and passes into the header 19 and from thence into the atomizers, finally passing through the holes 38 in a series of small continuous jets of steam 75 into the tubes 12. Oil passes intermittently from the oil measuring pumps 48 in the reservoir 21 through the pipes 22 into the atomizers 14 below the diaphragms 44, thereby causing the diaphragms to slightly yield by hydraulic 80 pressure at each impulse or delivery stroke of the pumps and raising the atomizer spindles intermittently off their seats 40 to introduce the desired amount of oil to meet the steam which has become highly superheated 85 in the tubes 12 while awaiting the intermittent 90 injection of the oil, where the steam and oil become intimately mixed. The mixture travels down the tubes 12 and upon coming into contact with the heated walls thereof becomes heated to a sufficiently high temperature 95 to cause dissociation of a quantity of the steam present in the tubes into free hydrogen and oxygen in the presence of the nickel catalyst and reaction between hydrogen and carbon, thereby producing oil gas which 100 passes out of the lower ends of the tubes 12 into the annular spaces between the retorts 9 and tubes 12 and thence through the annular header 7 and the pipe 23 into the scrubber 105 and finally to the gas mains.

It is to be noted that while the steam is supplied in continuous jets and the oil is supplied intermittently as previously mentioned, that it is advantageous to have a surplus supply of steam as the experiments on my oil gas generator have shown that the quantity of initial steam has very little bearing on the quality of the gas, as apparently the hydrocarbons combine with a definite quantity of hydrogen from the dissociated steam and the surplus steam is carried over and condensed in the scrubber. Moreover, it is desirable to maintain a surplus of steam in order that the process may be effectively carried out continuously. The excess steam also serves to prevent carbon deposits in the retorts.

The following is given as a specific example of carrying out the process, but it is to be understood that the invention is not restricted to the particular example of proportions, etc.

Oil, such as petroleum for example, is introduced with steam into the tubes 12 and the oil gas generator is fired at such a rate that the 130

temperature around the retorts 9 is 1600° F. to 1900° F. more or less.

I claim:

1. In apparatus for generating oil gas, a furnace, a series of vertically disposed retorts extending into said furnace and having their lower ends closed, a series of tubes extending respectively into each of said retorts and having their lower ends open and individually timed atomizers attached to the upper ends of each of said tubes for introducing steam and oil and producing oil gas in said tubes, said atomizer having movable spindles attached to diaphragms which are hydraulically and intermittently operated, means for controlling the sequence or rotation in which the atomizers are operated with respect to each other, and a header to which the said retorts are attached for receiving the products of said oil gas generation.

2. In apparatus for generating oil gas, a furnace, a series of vertically disposed retorts extending into said furnace and having their lower ends closed and being connected at their upper ends to a common header, a series of tubes extending respectively into each of said retorts and having their lower ends open, individually timed atomizers at the upper ends of said last named tubes, means to introduce steam continuously into said atomizers, and to introduce oil intermittently into said atomizers in measured quantities.

3. In apparatus for generating oil gas, a furnace, an exit for waste gases at the upper portion of said furnace, a series of vertically disposed tubes surrounding said exit and extending into said furnace and having their lower ends closed, a header in the upper portion of said furnace to which the upper ends of said tubes are connected, another series of tubes extending into said first named series and having their lower ends open, and individual hydraulically operated atomizers to introduce steam and oil into the upper ends of each of said last named tubes by means of individual oil measuring pumps.

4. In an oil gas generating apparatus having a plurality of retorts and an atomizer for each individual retort, means to intermittently atomize and introduce the oil from which the gas is to be made into said retorts in a predetermined sequence, and separate means for delivering a constant supply of jets of steam directly into said retorts during the oil gas generation in the entire apparatus.

5. In an oil gas generator having a plurality of retorts, means to measure oil and introduce it into each individual retort intermittently in a momentary period of time, separate means for introducing a continuous supply of steam directly into said retorts, said retorts operating in an overlapping sequence and generating a continuous supply of gas in the generator as a whole while the temperature of the individual retorts is main-

tained due to the said intermittent and independent operation of the retorts.

6. In an oil gas generator, a plurality of retorts, each having a movable spindle type atomizer for introducing oil into said retorts, hydraulic means to operate the oil admitting spindle of the atomizers intermittently, thereby maintaining a predetermined temperature in each individual retort, said means comprising individually timed single acting oil measuring pumps, said pumps being arranged in multiple, and having means for varying the operation of the retorts in sequence or rotation.
